DISPOSABLE DIAPER

Margaret E. Miller, New York, N. Y.

Application November 3, 1950, Serial No. 193,774

9 Claims. (Cl. 128—287)

1

The present invention relates to new and useful improvements in moisture-absorbing articles of clothing and relates more particularly to a disposable diaper.

An object of the invention is to provide a diaper that is completely disposable and one that does not require the use of pins or snaps to hold it in place. Another object of the invention is to provide a diaper that is shaped to provide a comfortable fit for the infant and that does not require folding in the manner that cloth diapers do to provide for sufficient absorption.

A further object of the invention is to provide a diaper of the disposable type that may be readily adjusted by the user to fit infants of various sizes. Other objects and advantages of the invention will be apparent and best understood from the following description and the accompanying drawings in which:

Fig. 1 is a plan view of a diaper embodying the invention;

Fig. 2 is a section view taken along the line 2—2 of Fig. 1;

Fig. 3 is a fragmentary view in section and illustrates a modification of the invention;

Fig. 4 is an end view of a portion of a diaper with the sides of the top and bottom in overlapping relation; and

Fig. 5 is a side view of the portions of the diaper illustrated in Fig. 4.

Referring now to the drawings in detail, there is a diaper, indicated generally by the reference numeral 10, which is shaped so that it can be placed on an infant easily and without special folding. The diaper 10 is shown in its flat condition in Fig. 1 and consists of an inner sheet or lining 11 and an outer sheet 12 which are superimposed on each other.

The sheets 11 and 12 are shaped to form a front portion 13 and a back portion 14 which extend around the waist of an infant when the diaper is doubled on itself. The sides of the sheets 11 and 12 are curved inwardly as indicated at 15 to form a crotch portion 16 of reduced width which extends between the legs of the infant. The inward curvature 15 of the sides also provides circular-shaped openings that are designed to accommodate the legs of the infant when the diaper is doubled and is secured in place on the infant.

The inner sheet 11 is made of thin sheet material such as a tissue paper or rayon pulp cloth which is absorbent and has wet strength. Such material will not disintegrate or tear readily when it becomes wet in use and in addition, it

2

will not adhere to the infant's skin. If desired, this material for the inner sheet 11 may be sterilized and it may also be impregnated with an antiseptic or other medication to retard any possible infection the infant may have or to counteract irritation of the infant's skin due to contact with body wastes.

The outer sheet 12 is made of a material such as a wet-proof paper that prevents moisture from reaching the outside of the diaper and wetting other items of clothing which the infant may be wearing. A suitable water-repellant paper is one that has been treated or impregnated with a coating of polystyrene on its outer surface.

5 A filler 17 made of cellulose or similar pulp material is interposed between the inner and outer sheets 11 and 12. Such a filler is very absorbent and may be easily sterilized. The filler 17 has the same general contour as the inner and outer sheets 11 and 12, but is somewhat smaller in size with its edges being spaced inwardly from the edges of the inner and outer sheets. This keeps the diaper from becoming bulky or unwieldy at the side edges thereof.

10 20 25 A supplemental filler 18 of cellulose material, similar to the filler 17, is also interposed between the inner and outer sheets 11 and 12 at the crotch portion 16 of the diaper. The supplemental filler 18 is T-shaped with the top of the T being located toward the back portion 13 of the diaper and with the leg of the T extending over the crotch portion and toward the front portion 14 of the diaper. The supplemental filler 18 is thus positioned so as to provide extra padding of the absorbent filler material where it is most needed; i. e., in the back for girls and in the front for boys.

30 35 The inner and outer sheets 11 and 12 are secured together with the fillers 17 and 18 between them by folding the edge of one of the sheets over the edge of the other sheet as indicated at 19 in Fig. 2. The folded edge may be secured in place by adhesives or other suitable means and provides a finished edge for the diaper.

40 45 50 55 After the various parts of the diaper have been placed in their proper positions, they are then pressed together along lines 20 extending across the diaper. This forms creases along the lines 20 which extend through the inner and outer sheets and the fillers. The crease lines 20 may be in the form of diamond or square-shaped patterns which give the diaper the appearance of being quilted and they will appear on both sides of the diaper. Such crease lines 20 tend to hold the filler 17 and 18 against movement relative to

the inner and outer sheets and they also form a plurality of moisture-retaining cells in the fillers that tend to prevent moisture from dissipating throughout the whole diaper and therefore reduces the possibility of irritation, chafing and discomfort when the diaper is wet.

Tabs 21 and 22 are provided at the sides of the back portion 13 and the front portion 14, respectively, of the diaper. The tabs 21 and 22 on the back and front portions of the diaper, respectively, overlap, as indicated in Fig. 4, when the diaper is double and placed on an infant. These tabs 21 and 22 may each be provided with one or more lengthwise perforations, as indicated at 23, so that portions of the tabs may be readily torn off to adjust the diaper to fit various sizes of infants.

A strip of tape 24 extends beyond the tabs 23 on the back portion of the diaper. The tape 24 may be an adhesive tape or other suitable tape such as a cellulose tape having a pressure-sensitive adhesive on one surface and it may be attached to the portion of the diaper as illustrated or supplied separately for attachment by the user. Thus, when the tabs on the back and front portions 13 and 14 of the diaper are in overlapping relation, as shown in Figs. 4 and 5, the tape 24 is merely pressed into contact with both of the portions where they join and this secures the diaper snugly in place without the use of pins or snaps. This eliminates any danger of the infant being stuck by safety pins and there is no tendency to tear the paper as would be the case if pins were used.

In the modification illustrated in Fig. 3, an inner sheet 11a is provided with perforations as indicated at 25. The perforations 25 may be formed by piercing the inner sheet 11a at the same time as the creases along the intersecting lines are formed and they should be of a sufficient size to permit moisture to pass through the paper readily.

A diaper made in accordance with the present invention is completely disposable and no part of the diaper need be saved or laundered. The cost of the diaper is such, however, that the expense of using such diapers will be very little, if any, more than the cost of the usual cloth diapers plus the cost of laundering such diapers. In addition, the present diaper possesses many advantages in convenience for the mother and in comfort and cleanliness for the infant.

It will be understood that various modifications and changes in the embodiment of the invention illustrated and described herein may be made by those skilled in the art without departing from the scope of the invention as defined by the following claims.

I claim:

1. In a disposable diaper the combination of an outer sheet of water-repellant paper, an inner sheet of water-penetratable material having wet-strength, said inner and outer sheets being secured together at their edges by folding the edge of one of the sheets over the edge of the other sheet and being shaped to form a front portion and a back portion connected by a crotch portion of reduced width, a filler of absorbent cellulose material located between said inner and outer sheets and a supplemental filler located between the inner and outer sheets and extending across the crotch portion thereof, said supplemental filler being T-shaped and having the top of the T located toward the back portions of the inner and outer sheets.

2. In a disposable diaper the combination of an outer sheet of water-repellant paper, an inner sheet of water-penetratable material having wet-strength, said inner and outer sheets being secured together and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer sheets and creases along intersecting lines extending across the surfaces of and through said sheets and fillers, said creases dividing the fillers into a plurality of moisture-retaining cells.

3. In a disposable diaper the combination of an outer sheet of water-repellant paper, an inner sheet of water-penetratable material having wet-strength, said inner and outer sheets being secured together and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer sheets and tabs extending from the side edges of the front and back portions of inner and outer sheets, said tabs having lengthwise perforations therein for detaching portions thereof from the inner and outer sheets.

4. In a disposable diaper the combination of an outer sheet of water-repellant paper, an inner sheet of water-penetratable material having wet-strength, said inner and outer sheets being secured together and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer sheets, creases along intersecting lines extending across the surfaces of and through said sheets and fillers, said creases dividing the fillers into a plurality of moisture-retaining cells and tabs extending from the side edge of the front and back portions of the inner and outer sheets, said tabs having lengthwise perforations therein for detaching portions thereof from the inner and outer sheets.

5. In a disposable diaper the combination of an outer sheet of water-repellant paper, an inner sheet of water-penetratable material having wet-strength, said inner and outer sheets being secured together and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer

sheets, tabs extending from the side edges of the front and back portions of inner and outer sheets, said tabs having lengthwise perforations therein for detaching portions thereof from the inner and outer sheets, and means for securing the front portion of the sheets to the back portion of the sheets in overlapping relation, said means comprising a tape having a pressure-sensitive adhesive extending lengthwise of the sides of the back and front portions of the sheets and engaging with said front and back portions.

6. In a disposable diaper the combination of an outer sheet of water-repellant paper, an inner sheet of water-penetratable material having wet-strength, said inner and outer sheets being secured together at their edges and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer sheets, creases along intersecting lines extending across the surfaces of and through said sheets and fillers, said creases dividing the filler into a plurality of moisture-retaining cells, tabs extending from the side edges of the front and back portions of the inner and outer sheets, said tabs having lengthwise perforations therein for detaching portions thereof from the inner and outer sheets, and means for securing the front portion of the sheets to the back portion of the sheets in overlapping relation, said means comprising a tape having a pressure-sensitive adhesive on one surface thereof, said surface engaging with said front and back portions of the sheets adjacent the point at which they overlap.

7. In a disposable diaper the combination of an outer sheet of water-repellant paper, an inner sheet of water-penetratable material having wet-strength and having a series of perforations therein extending over its surface, said inner and outer sheets being secured together and being shaped to form a front portion and a back portion connected by a crotch portion of reduced width, a filler of absorbent cellulose material located between said inner and outer sheets and a supplemental filler of absorbent cellulose material located between the inner and outer sheets and extending across the crotch portion thereof,

said supplemental filler being T-shaped and having the top of the T located toward the back portions of the inner and outer sheets.

8. In a disposable diaper the combination of an outer sheet of water-repellant paper, an inner sheet of water-penetratable material having wet-strength and having a series of perforations therein extending over its surface, said inner and outer sheets being secured together and being shaped to form a front portion and a back portion connected by a crotch portion of reduced width, a filler of absorbent cellulose material located between said inner and outer sheets, a supplemental filler of absorbent cellulose material located between the inner and outer sheets and extending across the crotch portion thereof, said supplemental filler being T-shaped and having the top of the T located toward the back portions of the inner and outer sheets and creases along intersecting lines extending across the surfaces of and through said sheets and fillers, said creases dividing the fillers into a plurality of moisture-retaining cells communicating with the perforations in the inner sheet.

9. In a disposable diaper, the combination of an outer sheet of water-repellant paper, an inner sheet of water-absorbent paper, said water-absorbent paper being of a type having strength when wet, said inner and outer sheets being secured together along their sides and being shaped to form a front portion and a back portion connected by a crotch portion of reduced width, a filler of absorbent cellulose material located between said inner and outer sheets, creases along intersecting lines extending across the surface of at least one of the sheets and through the filler, said creases dividing the filler into a plurality of moisture-retaining cells and securing means extending outwardly from opposite sides of the front and back portions formed by the inner and outer sheets.
